US00D845962S

(12) **United States Design Patent** (10) **Patent No.:** **US D845,962 S**
(45) **Date of Patent:** **** Apr. 16, 2019**

(54) **BASE PORTION OF A PORTABLE DEVICE HOLDER**

- (71) Applicant: **Kenu, Inc.**, San Francisco, CA (US)
- (72) Inventors: **David E. Yao**, San Francisco, CA (US); **Leonard John Duran**, Mill Valley, CA (US); **Gregory D. Caneer**, Oakland, CA (US); **Kenneth Y. Minn**, San Francisco, CA (US)
- (73) Assignee: **KENU, INC.**, San Francisco, CA (US)
- (**) Term: **15 Years**
- (21) Appl. No.: **29/663,050**
- (22) Filed: **Sep. 11, 2018**

(57) **CLAIM**

The ornamental design for a base portion of a portable device holder, as shown and described.

DESCRIPTION

FIG. 1 is a rear perspective view of a base portion of a portable device holder;

FIG. 2 is a front perspective view of the base portion of the portable device holder;

FIG. 3 is a front elevational view of the base portion of the portable device holder;

FIG. 4 is a rear elevational view of the base portion of the portable device holder;

FIG. 5 is a bottom plan view of the base portion of the portable device holder;

FIG. 6 is a top plan view of the base portion of the portable device holder;

FIG. 7 is a right elevation view of the base portion of the portable device holder; and,

FIG. 8 is a left elevation view of the base portion of the portable device holder.

The broken lines in FIGS. 1-3 and 6-8 represent unclaimed portions of the claimed design and form no part of the claimed design.

1 Claim, 4 Drawing Sheets
